US00D734662S

(12) **United States Design Patent**
Miller et al.

(10) **Patent No.:** US D734,662 S
(45) **Date of Patent:** ** Jul. 21, 2015

(54) **MEDICAL DEVICE PACKAGE**

- (71) Applicants: **INTERSURGICAL AG**, Vaduz (LI);
Muhammed Aslam Nasir, Caddington,
Bedfordshire (GB)
- (72) Inventors: **Andrew Miller**, Crowthorne (GB); **Jane Kemp**, Wokingham (GB)

- (73) Assignees: **INTERSURGICAL AG** (LI);
Muhammed Aslam Nasir (GB)

(**) Term: **14 Years**

(21) Appl. No.: **29/475,489**

(22) Filed: **Dec. 3, 2013**

Related U.S. Application Data

- (62) Division of application No. 29/416,561, filed on Mar. 23, 2012, now Pat. No. Des. 712,244.

(30) **Foreign Application Priority Data**

(57) **CLAIM**

The ornamental design for a medical device package, as shown and described.

DESCRIPTION

FIG. 1 is an open top view of packaging for a medical device, showing our new design;

FIG. 2 is an open bottom view thereof;

FIG. 3 is a closed right side view thereof;

FIG. 4 is a perspective open bottom view thereof;

FIG. 5 is a perspective open top view thereof;

FIG. 6 is a perspective closed top view thereof; and,

FIG. 7 is a perspective closed bottom view thereof.

The broken lines in the drawings illustrate unclaimed environment only and form no part of the claimed design.

1 Claim, 7 Drawing Sheets
